PASTRY SHEET OR THE LIKE

Robert Daenen, Erembodegem, Belgium, assignor to Dart Industries Inc., Los Angeles, Calif.

Continuation-in-part of design application Ser. No. 22,995, May 15, 1970. This application May 4, 1971, Ser. No. 140,317

Term of patent 14 years

Int. Cl. D7—04

U.S. Cl. D7—85

The sheet is of no substantial thickness and the opposite surface to that shown is substantially plain and unornamented.

This is a continuation-in-part of design application Ser. No. 22,995, filed May 15, 1970 and now abandoned.
I claim:

The ornamental design for a pastry sheet or the like, as shown and described.
